WITNESS:

R. Hamilton

INVENTOR.
William P. Pitt
BY
Warren D. House
His ATTORNEY

UNITED STATES PATENT OFFICE.

WILLIAM P. PITTS, OF KANSAS CITY, MISSOURI.

RECORD-SHEET.

1,330,216.

Specification of Letters Patent. Patented Feb. 10, 1920.

Application filed March 21, 1917. Serial No. 156,482.

To all whom it may concern:

Be it known that I, WILLIAM P. PITTS, a citizen of the United States, residing at Kansas City, in the county of Jackson and State of Missouri, have invented a certain new and useful Improvement in Record-Sheets, of which the following is a specification.

My invention relates to improvements in record sheets.

The object of my invention is to provide a novel record sheet by means of which an accurate schedule and record may be easily made with reference to certain acts performed at certain periods.

My invention is particularly well adapted for use in connection with the lubricating of certain parts of an automobile at certain periods of miles traveled by the machine.

One of the objects of my invention is to enable the operator of a machine to determine at a glance what acts are to be performed with reference to the running or use of the machine at various periods of miles traveled by the machine; and also to enable the operator to keep an accurate record of what acts designated by the schedule have or have not been performed at certain predetermined periods of travel.

The novel features of my invention are hereinafter fully described and claimed.

In the drawing, I have illustrated the preferred embodiment of my invention as applied to a schedule and record of the lubrication of a car of a certain type.

1 designates the record sheet ruled with vertical lines 2 which cross horizontal lines 3, thereby forming vertical rows of spaces 4 and horizontal rows of spaces 5.

40 The vertical rows 4 are provided with headings 6 designating certain periods, such as miles traveled. The first row of vertical spaces, which is the one at the left, as shown in the drawing, has no heading and represents the period at which the lubrication begins, that is at the beginning of the travel of the machine.

The next vertical row 4 has the heading 500, designating the period at the end of 50 five hundred miles travel. Each succeeding heading 6 to the right of the heading 500

increases five hundred in numerical value over the heading next to the left. The schedule illustrated is arranged for eight thousand miles of travel and contains seventeen vertical rows of spaces 16 each of which have headings of a numerical value comprising multiples of five hundred.

The horizontal rows of spaces 5 are respectively provided with headings 7, which 60 respectively designate certain acts to be performed, at certain periods of travel. In the schedule shown, there are twenty eight headings 7 corresponding to the twenty eight horizontal rows of spaces. The headings 7 may be such as will direct the operator in the performance of the different acts required to be performed with the particular car to which the schedule and record is adapted. In the particular schedule illustrated, the heading in the uppermost horizontal row 5 is as follows "Fill oil cup in generator under floor board O." The heading next below is "Turn down 14 spring shackles grease cups." The succeeding 70 headings instruct as to the other acts to be performed in lubricating other parts of the machine.

After a certain number of miles have been traveled, certain parts of the machine should 80 be lubricated, while other parts need not, at that period, be lubricated. At the start of travel all of the acts designated by the headings 7 should be performed. At that time, if such acts are thus performed, the 85 operator enters in the vertical row at the left check marks 8 in the horizontal rows 5, thus making a record showing that such acts have all been performed at the time mentioned.

At the end of a period of five hundred miles travel, the acts designated by the first thirteen headings should be performed. With the particular machine for which this particular schedule is designed, at the end 95 of one thousand miles travel, the acts designated by all of the twenty one headings should be performed. At the end of fifteen hundred miles travel, at twenty five hundred miles travel and at thirty five hundred miles travel, all of the acts designated by the first thirteen headings should be per-

formed. At the end of two thousand miles travel, the acts designated by the first twenty four headings should be performed. At the end of three thousand miles travel, the acts 5 designated by the first twenty one headings should be performed, and at the end of four thousand miles travel, all of the acts designated by the twenty eight headings should be again performed, the same as at the start 10 of travel. This completes the cycle, following which the operations above described should be repeated.

As the operator performs any of the various acts required by the schedule, he should 15 enter a check mark 8 in the appropriate space of the proper vertical and horizontal rows 4 and 5 respectively. He will thus have a record by which he can at any time determine just what acts have been per 20 formed and what have not been performed. Thus at the end of one thousand miles travel, he may have failed to have performed the acts designated in the fifth and eleventh headings 7. As no check marks 8 25 appear in the vertical row having the heading 1000 and opposite the fifth and eleventh headings 7, the record will show such omission.

In order that the operator may know just 30 what acts are to be performed at the end of each period of travel of five hundred miles, there is provided indicating means which instruct him what acts need not be performed at any of such periods of travel.

35 Such indicating means consist, preferably, in vertical wide lines 9 located in the vertical rows having the headings 500, 1500, 2500, and 3500 respectively. The lines 9 cross the last fifteen horizontal rows 5. Similar vertical lines 10 located in the vertical rows respectively which have the headings 1000 and 40 3000, extend across the last seven horizontal rows 5.

A similar vertical line 11 located in the 45 vertical row having the heading 2000 extends across the last four horizontal rows 5.

The lines 9, 10 and 11 indicate to the operator that the acts designated by the headings in the rows 5 crossed by said lines need 50 not be performed at the periods respectively represented by said lines, and that check entries 8 will, therefore, only be entered in the spaces which are directly above the upper ends of said lines.

55 In the operation of my invention, at the start of travel, the operator is presumed to perform all the acts designated in the twenty-eight headings. If he does so, he should enter check marks 8 opposite said 60 headings respectively, in the first vertical row of spaces at the left.

At the end of five hundred miles travel, the left vertical line 9 instructs him that the first thirteen acts are to be performed.

65 At the end of one thousand miles travel, the

left vertical line 9 indicates that the first twenty-one acts are to be performed. At the end of fifteen hundred miles travel, the next vertical line designates that the first thirteen acts are to be performed. At the 70 end of two thousand miles travel, the line 11 indicates that the first twenty-four acts are to be performed. At the end of four thousand miles, the entire twenty-eight acts are to be repeated. Such acts as the operator performs are indicated in the record by the entries of the check marks 8 in their appropriate places. The operator is thus 75 enabled at a glance to determine the state of lubrication of the car at any period of 30 travel.

I do not limit my invention to the structure shown and described, as modifications, within the scope of the appended claims, may be made without departing from the 80 spirit of my invention. It will be understood that the various headings employed may be changed to adapt the schedule and record to any type of car, and it will be understood that the particular indicating 85 means employed, corresponding to the lines 9, 10 and 11, may be so arranged and disposed as to adapt the schedule and record to the particular use to which it may be put. While I have illustrated and described the 90 invention as applied to the lubrication of a car, it will be obvious that the invention is adapted for use as a schedule and record sheet in connection with any certain series 95 of acts which are to be performed at different 100 periods, either of time or travel.

What I claim is:—

1. A record sheet ruled so as to provide vertical and horizontal rows of spaces, the vertical rows having headings respectively 105 designating miles traveled, and the horizontal rows having headings respectively designating certain acts to be performed, some of the horizontal rows having means indicating that the acts designated by the headings 110 thereof are not to be performed at the periods represented by the miles traveled.

2. A record sheet ruled so as to provide vertical and horizontal rows of spaces, the vertical rows having headings respectively 115 designating miles traveled, and the horizontal rows having headings respectively designating certain acts to be performed, some of the vertical rows being provided respectively with lines extending across certain of 120 the horizontal rows, and indicating that the acts designated by the headings of the rows so crossed are not to be performed at the periods which said lines respectively represent.

3. A record sheet ruled so as to provide vertical and horizontal rows of spaces, the vertical rows having headings respectively 125 designating miles traveled, and the horizontal rows having headings respectively design-

nating certain acts to be performed, some of the vertical rows being provided respectively with lines extending across certain horizontal rows, and indicating that the acts designated by the headings of the rows so crossed are not to be performed at the periods which said lines respectively represent, some of

said lines being extended across a greater number of horizontal rows than others of said lines.

10

In testimony whereof I have signed my name to this specification.

WILLIAM P. PITTS.
